CLAIM

The ornamental design for a filter housing with tube ports,
as shown and described.

DESCRIPTION

FIG. 1 is a rear perspective view of a first half of a filter
housing with tube ports in accordance with our design;
FIG. 2 is a rear elevation view thereof;
FIG. 3 is a side elevation view of the left side thereof, the
right side being a mirror image of the left side;
FIG. 4 is a front elevation view thereof;
FIG. 5 is a top plan view thereof;
FIG. 6 is a front perspective view thereof;
FIG. 7 is a front perspective view of a second half of a filter
housing with tube ports in accordance with our design;
FIG. 8 is a front elevation view thereof;
FIG. 9 is a side elevation view of the left side thereof, the
right side being a mirror image of the left side;
FIG. 10 is a rear elevation view thereof;
FIG. 11 is a bottom plan view thereof; and,
FIG. 12 is a rear perspective view thereof.
FIGS. 1-6 showing the first half of the filter housing and
FIGS. 7-12 showing the second half of the filter housing, are
parts of a set.
The broken line showing of parts of the drawings is included
for the purpose of illustrating use and environment and
forms no part of the claimed design.

1 Claim, 12 Drawing Sheets
